[57] CLAIM

The ornamental design for a table, as shown and described.

DESCRIPTION

FIG. 1 is a perspective view of a table showing my new design;

FIG. 2 is a side view thereof, the opposite side being a mirror image of the side shown;

FIG. 3 is a top plan view thereof; and,

FIG. 4 is an end view thereof, the opposite end being a mirror image of the end shown.

The table of the design is shown with an extension leaf secured at one end thereof.
